LUTHER O. CROCKER, OF BRAINTREE, MASSACHUSETTS.

Letters Patent No. 95,091, dated September 21, 1869.

IMPROVEMENT IN TICKET-CUTTERS.

The Schedule referred to in these Letters Patent and making part of the same.

To all persons to whom these presents may come:

Be it known that I, LUTHER O. CROCKER, of Braintree, of the county of Norfolk, and State of Massachusetts, have made a new and useful invention having reference to Ticket-Cutters or Punchers; and do hereby declare the same to be fully described in the following specification, and represented in the accompanying drawings, of which—

Figure 1 is a side elevation, and

Figure 2 an end view of a ticket-cutter or punch, provided with my said invention.

Figure 3 is a top view of the clearer, and

Figure 4 is a transverse section of the clearer and the male die or cutter.

The invention in question relates particularly to punchers used by railway-carriage conductors, for the cancelling or cutting of holes in passage-tickets, the object of the invention being to render the punchers easily operated and very durable.

In the drawings—

a denotes the upper, and *b* the lower jaw, jointed together at *c*, and having handles *d* *e*, as seen in fig. 1.

From the outer end of the lower handle *d*, a steel wire, *f*, extends between the handles, its end passing into and working loosely in the other handle *e*, close to the joint.

Near the handle *d* this wire is formed with a finger-slot or recess, *g*, by which the instrument may be held upon the finger when not in direct use; and between the projection or bend forming this finger-piece and the handle *e*, a spiral spring, *h*, surrounds the wire, the stress of the spring keeping the handles normally apart, as will be readily understood.

Now, as usually made, this wire is itself the distending-spring, it being fixed at one end to the inner surface of one of the handles, and bearing at its other end directly against the inner surface of the other handle.

In such application, however, so much stress comes directly upon the spring that it is liable to soon become broken, thus rendering the instrument useless for the time, or until the spring can be replaced by the maker; but by carrying the end of the wire into the handle, and allowing it to play loosely in or through the same, and applying the spring *h* to force apart the handles, no particular stress comes upon the wire, and the liability of the spring-wire to break is entirely overcome.

To the jaw *a* is fixed the die *i*, having a cutting-face or edge corresponding to the letter or cancelling-mark or designation to be cut in the card, this die operating in connection with a counter die of corresponding form or outline in the opposite jaw, as in other punches of this character.

Ordinarily, however, the card, after having been cut, will be cleared from the male die by a spring acting as a stripper, this spring being fastened to the jaw, and bent around into the plane of the die-face, as seen at *x*, in Figure 5, a rubber spring, *y*, being sometimes interposed between the spring and jaw to increase the action of the stripper. Such strippers, however, soon break or become unserviceable, and have to be forced below the cutting-face of the die by the direct action of the operating face of the counter-die jaw.

To remedy this defective construction, I apply, to the male die *i*, a rigid stripper-plate, *k*, having no flexibility or elasticity in itself, but being supported at its outer end against one or more springs *l*, connected to the die-jaw.

The stripper-plate is hinged or jointed at its inner end to, and so as to move with the other jaw, the connection being near the joint *c*, as seen at *m*.

The connecting-pins, around which the springs *l* are wound, should be headed at their lower ends, so that, while the stripper can be compressed against such springs, its normal position will be regulated and determined by these pins, while the action of the spring which opens the handles brings the inner end of the stripper into normal position, in which position the acting surface of the stripper is in a plane with the acting surface of the die.

Now, when a card is inserted between the die-jaws, and the handles are brought together, the movement of one jaw toward the other will force the stripper above the die-face and leave the die free to cut, or free from pressure of the stripper at such face during most of its cutting action, the face of the counter-die jaw only having to force the stripper up at the outer point of the die.

When the card is cut, the action of the springs *l* forces the stripper down, and releases the card at the outer end of the die only, the action of the spring *h* in separating the handles producing most of the movement of the stripper-plate, by reason of the plate being hinged to the jaw *b*, as shown at *m*.

To facilitate the cutting action of the die, I bevel the face thereof, both laterally and longitudinally, so that the die commences to cut at one side and end thereof, instead of equally or simultaneously upon both sides, or along its whole cutting-edge.

The instrument thus made is found to be very enduring, having no springs, which are very liable to break, and having the cutter and stripper so arranged and operated that a card will always be cut, and be cleared from the instrument, after being cut, with ease and facility.

A stout rubber spring may be placed over the inner end of the stripper to force the card from the die, the

end of the stripper being extended up into the joint slot of the instrument, so that the stripper may be moved away from the die-face as the jaws begin to close; but the specific construction shown is considered preferable.

I claim the combination of the stripper *k* with the die-jaws, substantially in manner and so as to operate therewith, and with the dies, as specified, the stripper under such a combination having its inner end jointed to the lower jaw, and its other end supported against one or more springs, and provided with stops, as set forth.

I claim the wire *f*, as made, with the finger-bend or recess *g*.

I also claim the arrangement and combination of

the wire *f*, and the finger-recess thereof, with the spring *h*, and the two jaw-levers provided with cutting-dies, or the same, and a stripper, as explained.

I also claim, in combination with the stripper-plate *k*, the inclination of the cutting-face of the die *i*, longitudinally or laterally, or in both directions, relatively to the lower face of the said stripper-plate, so that the stripper-plate, when in the act of clearing a card from the die, may effect the same in a gradual manner from end to end or side to side, or in both ways, of the cut made by the die.

LUTHER O. CROCKER.
